SHOOTING JACKET

Howard O. Smith, Des Moines, Iowa

Application January 29, 1936, Serial No. 61,329

3 Claims. (Cl. 2—94)

The principal object of my invention is to provide a shooting coat or jacket that is so padded and designed that great comfort is afforded in use.

5 A further object of this invention is to provide a target shooting garment that is successfully padded against the usual discomfort experienced from the rifle sling strap.

A still further object of my invention is to provide a shooting garment for prone, kneeling, sitting, and standing shooting positions.

A still further object of this invention is to provide a padded shooting garment that is refined in appearance, durable in use, and economical in manufacture.

15 These and other objects will be apparent to those skilled in the art.

My invention consists in the construction, arrangement and combination of the various parts of the device, whereby the objects contemplated 20 are attained as hereinafter more fully set forth, pointed out in my claims and illustrated in the accompanying drawing, in which:

Fig. 1 is a front view of my garment ready for use.

25 Fig. 2 is a left side view of my garment in use. Fig. 3 is a cross-sectional view of the left arm sleeve of my garment taken on line 3—3 of Fig. 1.

Fig. 4 is a cross-sectional view of the left arm sleeve of my garment taken on line 4—4 of Fig. 2.

30 Shooting garments are universally used by sportsmen and are intended to provide comfort to the shooter and increase the accuracy of his shooting. Such garments usually have a pad element over each elbow portion, and a pad element at the gun butt arm socket. Such garments I find, however, do not have a properly 35 designed or positioned pad element around the upper portion of the arm of the wearer where the gun sling strap embraces it. I have overcome such objections by providing a shooting garment giving freedom of movement and having a self-adjusting pad element extending substantially around the upper portion of the gun sling 40 arm of the user.

45 Referring to the drawing, I have used the numeral 10 to generally designate my shooting coat or jacket having the usual sleeves 11 and 12. The numeral 13 designates the seam of the sleeve 50 12 which is the gun sling arm of the garment. In order that the garment provide maximum comfort and freedom, I recommend that it be of the inverted box pleat back type as shown in Fig. 2. The numeral 14 designates the shoulder arm- 55 pit pad element designed to be engaged by the

gun stock butt plate. Such pads aid in protecting the shooter's shoulder from the gun recoil at time of gun discharge and also frictionally yieldingly hold the gun butt in proper non-slip shooting position. The numeral 15 designates 5 the right sleeve elbow pad element and the numeral 16 designates the left sleeve elbow pad element. The numeral 17 designates my gun sling pad element extending substantially around the left sleeve 12 and overlapping the sleeve seam 10 13, as shown in Fig. 1.

All such pad elements are preferably of pliable leather and are formed by sewing their marginal edge portions to the garment 10, and placing padding material 18 such as kapok, cotton, felt, or like between the leather and garment, as shown in Fig. 3 and Fig. 4. The pad elements 15 and 16 are particularly desirable for prone shooting as they provide a suitable soft cushion for the elbows of the shooter. One of the chief features 20 of my garment, however, is the pad element 17. This pad element 17 is in the shape of a band extending transversely of the length of the sleeve 12 and has its two ends terminating a slight distance apart, as shown in Fig. 3. The inner end 25 portion of this element 17 substantially overlaps the seam 13, leaving the space between the two ends of the pad located as shown in Fig. 1. The top marginal edge of this pad 17 extends to a line just under the arm socket of the wearer and the 30 lower marginal edge terminates at a line substantially above the elbow of the wearer. The elongated elbow pad 16 which extends longitudinally of the sleeve 12 has its upper end portion overlapped by the pad 17. In the manufacture 35 of padded shooting garments, most pads are sewed on before the garment is sewed together. In the case of sleeves, the pads are sewed on and then the sleeves are sewed up and onto the body portion of the garment. Obviously, such pads 40 cannot overlap the sleeve seams. It will be noted, however, that the pad 17 does by necessity overlap the seam 13. I accomplish this by sewing the pad 16 completely on the sleeve and the pad 17 only partially on the sleeve before the sleeve itself 45 is sewed up. The pad 17 is sewed onto the sleeve to points near the seam 13 and then after the sleeve is sewed up the balance of the inner end portion is lapped over the seam 13 and sewed as shown in the drawing. A gun sling strap 19 50 completely embraces the arm with pressure on the back, outer side, and inner side of the arm.

Garment sleeves have seams on the inner side of the arm so it is obvious that the pad 17 must overlap the seam 13. This is particularly neces- 55

- sary as the large muscle of the arm substantially follows the seam line, and should be protected and padded. Also, it eliminates a cutting of the seam 13 into the arm by the gun sling pressure.
- 5 Still another advantage of my construction is that the coat sleeve will wrinkle when the gun sling is tightened upon it, as shown in Fig. 4, and this wrinkled condition should not occur on the back, inner, or outer side of the arm. Shooting
- 10 garments must have loose sleeves and by spacing the two ends of the pad apart, the sleeve wrinkles when the gun sling is tightened will naturally occur between the two ends of the pad 17. This important feature of my garment makes it automatically conform to the size of the arm of the shooter at the time of firing and the arm will be substantially completely surrounded by the pad 17, which is embraced by the loop of the gun sling. There will be no tendency for the sleeve
- 15 20 of the garment to wrinkle under the pad 17.
- The garment shown in the drawing is for right-handed shooters. Obviously, for left-handed shooters the pad 17 is on the right sleeve and the pad 14 on the left shoulder.
- 25 It will be noted that when shooting in the proper position the sling fits very tightly around the arm and the seam in the sleeve must not bind into the forearm. By using my construction, two ends of the sling pad are spaced apart and
- 30 the coat is permitted to wrinkle naturally at the forward side of the arm. This does not interfere as the gun sling only engages the arm in the back, on the inner side and at the outer side. By providing the gap in the front of the sling element,
- 35 the sling may be adjusted or tightened about the arm of the shooter. Furthermore, with my garment, the elbow pad and the sling pad work together, brace each other, and give complete, continuous and uniform support to the gun sling arm of the shooter. By overlapping one pad with the other, the sling strap may be easily removed from the arm as there are no projections or edges
- 40 of the pad to catch. Furthermore, there is no

tendency for wrinkling between the pads that are mutually supported by each other.

Some changes may be made in the construction and arrangement of my improved shooting garment without departing from the real spirit and purpose of my invention, and it is my intention to cover by my claims any modified forms of structure or use of mechanical equivalents which may be reasonably included within their scope.

I claim:

1. In a shooting garment, a body portion and a sleeve portion, a pad element on the back portion of said sleeve extending longitudinally of the longitudinal length of said sleeve, and a gun sling strap pad element having its ends spaced apart substantially at the front and extending transversally of the longitudinal length of said sleeve around the back, inner side and outer side of said sleeve with its lower marginal edge overlapping the upper edge portion of said first mentioned pad element.

2. In a shooting garment, a coat portion having a seamed sleeve, a pad element on the back portion of said sleeve extending longitudinally of the longitudinal length of said sleeve, and a gun sling strap pad element extending transversally of the longitudinal length of said sleeve around the back, inner side and outer side of said sleeve, overlying the seam of said sleeve and having its two ends spaced apart substantially at the front and its lower marginal edge portions overlapping the upper marginal edge portion of said first mentioned pad element.

3. In a shooting garment, a coat portion having a seamed sleeve and a gun sling strap pad element extending transversally around the back, inner side and outer side of said sleeve with one of its end portions overlapping the seam of said sleeve; said pad element being rigidly and permanently fixed to said sleeve and with a substantial space between its two ends substantially at the front for permitting the sleeve to wrinkle when the said pad is in use.

HOWARD O. SMITH.
